UNITED STATES PATENT OFFICE.

EVAN H. WADE AND JOHN L. NICHOLSON, OF CHICAGO, ILLINOIS, ASSIGNORS
TO AMERICAN LOCOMOTIVE EQUIPMENT COMPANY.

LOCOMOTIVE-BOILER FURNACE.

No. 851,329.

Specification of Letters Patent.

Patented April 23, 1907.

Application filed April 19, 1906. Serial No. 312,635.

To all whom it may concern:

Be it known that we, EVAN H. WADE and JOHN L. NICHOLSON, citizens of the United States, and residents of Chicago, Cook county, Illinois, have invented certain new and useful Improvements in Locomotive-Boiler Furnaces, of which the following is a full, clear, and exact description, such as will enable others skilled in the art to which it appertains to make and use the same.

Our invention relates to improvements in locomotive furnaces and has special reference to improvements upon the locomotive boiler furnaces which are shown and described in our pending applications, filed Sept. 13, 1904, serial numbers 224,305 and 224,306. The novel furnaces forming the subject-matter of said applications are characterized by front and back arches composed of refractory bricks, and each containing a number of air channels adapted to convey air to the inner ends of the arches, and to there discharge the same downwardly in converging streams. The lower ends of the front arches of these furnaces abut the front wall of the furnace in each case and the ducts therein are supplied with air through short tubes which extend through the front water leg at the throat of the boiler. The present invention is concerned with the shape or formation of the lower bricks of said front arches. We find many locomotive boilers wherein, by reason of the location of the arch tubes, or other reasons, it is impossible to arrange the air entrance tubes in line with the channels or ducts in our arches. In such locomotives we are unable to use arches having lower end bricks or sections of the kind shown in our pending applications, and the object of this invention is to so improve upon our previous inventions as to enable the use thereof upon engines of all classes.

A special object of this invention is to improve the form and construction of the lower bricks of the arch and adapt the same for use with air supply tubes that are arranged in and near the sides of the furnace.

Our invention consists generally in a locomotive boiler furnace, in combination with a refractory arch having its lower end in abutment with the flue sheet of the furnace, said arch being composed of a plurality of bricks containing communicating longitudinal passages or ducts, the lower end bricks of the

arch having their ducts extended laterally to 55 points in or near the sides of the furnace, and air tubes provided in the walls of the furnace and communicating with the ducts in said lower end bricks.

Our invention will be more readily understood by reference to the accompanying drawings, forming a part of this specification, and in which

Figure 1 is a vertical longitudinal section of a locomotive furnace embodying our invention; Fig. 2 is a horizontal section viewed from beneath, one-half of this view being on the line $x-x$ of Fig. 1, and the other half on the line $y-y$ of Fig. 1. Fig. 3 is a transverse vertical section on the line $z-z$ of Fig. 1; Fig. 4 is a longitudinal vertical section, illustrating an arch of a different type, the section being on the line $v-v$ of Fig. 5; Fig. 5 is a compound horizontal section of the structure of Fig. 4, similar in character to Fig. 2; 75 & Fig. 6 is a transverse section on the line $u-u$ of Fig. 4.

Referring to Figs. 1 to 3 of the drawings, it will be noted that the furnace is of an ordinary locomotive type. The rear end of 80 the furnace contains a short hollow arch, A, and the front a longer arch, B. The latter is composed of two series of bricks arched against each other and supported by lugs, 2, on the side walls of the furnace. See Figs. 1 85 and 3. The middle of the arch is composed of a number of bricks, B', of uniform shape, and together containing a plurality of straight longitudinal ducts, C. The upper end bricks, B², have cavities, C', and deflecting surfaces, B³, for discharging air toward 90 the furnace grate. The lower end bricks, D-D, are of still different shape and as these comprise the distinctive feature of the present invention, they will be described in detail. 95

The lower bricks abut against the lower part of the furnace flue sheet, 3. They take their form from the plane, B^a, of the lowermost bricks, B', and the plane or surface of the flue sheet, 3. In the opposite cross-section—that is, transversely of the furnace,—the bricks, D, correspond to the upper bricks of the arch. The ducts, C², in the bricks, D, are arranged at such angle that the outer duct, C², opens through the outer end of the 105 brick, and the inner and larger duct, C², opens through the bottom side of the brick, B, at the corner of the furnace. We prefer

that the larger duct shall communicate with the two inner ducts, C, of the abutting brick, B', while the duct C' is intended to supply only the outer channel or duct, C. The air is admitted to the duct through tubes, 4 and 5, extending through the front and side water legs of the boiler at points adjacent to the corner of the furnace. At such point, a tube, 4, may be arranged in the front water leg without interference with the cylindrical part of the boiler. The lower side of the brick, D, may be provided with notches, or cinder holes, D', if desired.

The front arch shown in Figs. 4 to 6 of the drawings and which is supported by arch tubes, 6, requires lower bricks of different form though possessing the same general characteristics as those above described. The arch shown in these figures has its lower end formed of two bricks, E—E, while its upper part comprises three rows or series of bricks, F, F & G, the latter having the form of keystones as shown in Fig. 6. The bricks, F, F & G contain air channels, F' and G', which are served with air through angular or diagonal ducts, E', E'', in the bricks EE. The ducts, E'—E'', are of irregular formation as required to communicate with the ducts, F and G, which are of varying elevations, as indicated. As before, the air tubes, 4' and 5', are arranged at the corners of the furnace, such location being most convenient in boilers of the type shown and such arrangement being made possible by the lateral ducts in the lower end arch brace.

Having thus described our invention, we claim as new and desire to secure by Letters Patent:

1. A locomotive boiler furnace, in combination with a front arch occupying an inclined position in the furnace and having its lower end abutting the flue sheet of said furnace and the upper part of said arch comprising longitudinally channeled refractory bricks, and the upper and lower bricks of said arch containing transverse channels, the latter communicating with the outer air, substantially as described.

2. A locomotive boiler furnace, in combination with a front arch therein, the lower end of said arch abutting the flue sheet of said furnace, said arch being composed of channeled bricks and the lower bricks thereof having transverse or lateral channels or ducts communicating with openings in the forward corners of said furnace, substantially as described.

3. A locomotive boiler furnace, in combination with a hollow refractory arch therein, said arch being composed of a plurality of 65 bricks and the lower bricks thereof each containing two angularly or diagonally positioned ducts communicating with the atmosphere, and the ducts in the upper part of the arch, substantially as described. 65

4. A locomotive boiler furnace containing laterally and longitudinally positioned air-admission tubes near its forward corners, in combination with a front arch comprising a plurality of longitudinally channeled refractory bricks, and two lower end bricks containing lateral or transverse channels or ducts communicating with respective tubes, substantially as described. 70

5. A hollow front arch for locomotive furnaces comprising lower end bricks in endwise abutment and containing lateral ducts opening through their ends and lower sides, and a plurality of channeled bricks superimposed upon said lower end bricks, substantially as 80 described.

6. A hollow front arch for locomotive furnaces comprising lower end bricks in endwise abutment and containing lateral ducts opening through their ends and lower sides, a plurality of bricks in sidewise abutment superimposed upon said end bricks, said superimposed bricks containing a plurality of longitudinal ducts, certain pairs of which communicate with single ducts in said lower end 85 bricks, substantially as described. 90

7. A hollow front arch for locomotive furnaces adapted to be supported on arch tubes, and comprising three rows or series of channeled refractory bricks in respective endwise 95 abutment, in combination with two lower end bricks in endwise abutment, and containing lateral ducts or channels communicating with the channels of the other bricks, substantially as described. 100
